UNITED STATES PATENT OFFICE.

HANS PETER RAVN, OF WATERLOO, IOWA.

ADJUSTABLE SCREEN.

Application filed December 9, 1921. Serial No. 521,169.

To all whom it may concern:

Be it known that I, HANS PETER RAVN, a citizen of the United States of America, and a resident of Waterloo, Blackhawk County, 5 Iowa, have invented certain new and useful Improvements in Adjustable Screens, of which the following is a specification.

My invention relates to improvements in adjustable screens, particularly to window 10 screens, and the object of my improvements is to supply a light, portable adjustably extensible and inexpensive screen, having means for releasably securing it to window jambs or the like.

15 This object I have accomplished by the means which are hereinafter described and claimed, and which are illustrated in the accompanying drawings, in which Fig. 1 is front elevation of the wire frame 20 work of my screen, having its parts extended adjustably to traverse a window opening, with its opposite ends releasably secured to bearing strips of the jambs, the flexible screen fabric not being shown. Fig. 25 2 is a front elevation of said frame work having its parts relatively adjusted to be of less length, and showing a flexible screen fabric covering it and removably secured thereto. Fig. 3 is an elevation of one of the 30 U-shaped frame members, Fig. 4 is an elevation of one of the removable slidably adjustable carrying rods for an end of the screen fabric, and Fig. 5 is an elevation of one of the resilient wire rods used as releasable fastening means for an end of the 35 frame. Fig. 6 is a longitudinal horizontal section of the complete device as shown in said Fig. 2. Fig. 7 is a vertical section of the frame only of said device as mounted 40 releasably between the side strips of a window jamb.

Similar numerals of reference denote corresponding parts throughout the several views.

45 The frame of my improved screen is composed of but six wire parts, and these parts consist of three sets or pairs of differently shaped wire elements which are shown in Figs. 3 to 5 inclusive. The open frame 50 proper is composed of a pair of like but reversed U-shaped wire rods bent rectangularly in places to supply in each instance a vertical medial part 1 and two horizontal, longitudinal and parallel arms or parts 2 55 and 3, each of said parts having a terminal hook or eye 4.

As shown in Fig. 1, said frame elements are positioned with parts of their arms along side each other and connected slidably adjustably by means of said hooks and eyes 4, 60 interlockingly.

Each bent rod shown in Fig. 4 comprises a vertical straight part 5 and a horizontal part 8 extending at a right angle therefrom, the connecting bend therebetween being a 65 loop 6, the outer or free ends of said parts 5 and 8 terminating in hooks 7 and 9 respectively. Each part 5 is positioned across frame arms 2 and 3, the hook 7 being seated over one arm, the hook 9 being seated upon 70 the other arm, and the last mentioned arm passed through said loop 6, whereby this rod 5 may be adjusted longitudinally along said members 2 and 3.

The end fastening means consist of a short 75 springy wire rod 10 having one end formed terminally into an eye 11 and hook 12, the eye being traversed by one of the other frame parts 2 or 3 as the case may be, near its angle to position the rod part 10 adjacent 80 the frame part 1. As indicated in Figs. 1 and 7, when the frame has been adjustably extended across a window opening to seat the parts 1 close to the jambs 16 between the strips 18 and under the raised sash 17, the 85 rod parts 10 can be sprung towards the part 1 and then released to engage the adjacent strip 18 to releasably hold that end of the screen frame work in place, with the hook 12 engaged with the part 1. 90

A flexible screen 13, which may be made of light porous cloth or wire netting is positioned to cover one side of the open frame work, and has its ends carried about the vertical end part 1 thereof to lie parallel to and closely abutting the opposite face of the frame work, and the ends of this screen are hemmed to provide transverse tubes 15 to receive the rod part 5 previous to the latter being mounted on said frame work. When the adjustable devices shown in Fig. 4 are so connected to the screen end and then mounted slidably on the respective frame members 2 and 3, these devices may be slidably adjusted along the frame-work to properly tensionally hold the screen thereon. 100

The particular function of the angularly directed part 8 of the bent rod 5 is to lie along the abutting frame-element and be 110 engaged therewith interlockingly although being slidably adjustable therealong longi-

tudinally. That is, the part 8 as connected to said frame-element by its terminal hook 9 tends to keep the part 5 of the rod in position across the frame-elements to properly support the ends of the screen 13 and keep the latter taut and smooth, but also interlocks with the abutting frame-element frictionally to resist ordinary forces tending to displace it. This device therefore will keep the screen positioned and taut in any adjustment of the frame-elements relatively to each other.

It is to be understood that various modifications may be made in my said device, without causing it to depart from the invention, or from the scope of its protection.

Having described my invention, what I claim as new and desire to secure by Letters Patent, is:

- 20 1. In a device of the character described, like U-shaped rods whose terminal members are interlockingly connected for relative longitudinal adjustments, and bent screen-holding rods having medial and terminal loops slidably mounted on said terminal members for relative longitudinal adjustments.
- 25 2. A device of the character described, comprising like U-shaped rods whose terminal members are reversely positioned and interlockingly connected for relative longitudinal adjustments, screen-holding rods positioned across said terminal members, and connected thereto for relative longitudinal adjustments, and a flexible screen positioned to cover one side of said U-shaped members and having its ends carried about the medial parts of said rods and connected removably to said screen-holding rods.
- 30 3. In a device of the character described, like U-shaped rods whose terminal mem-

bers are interlockingly connected for relative longitudinal adjustments, screen-holding elements mounted interlockingly on said terminal members for relative longitudinal adjustments, and resilient clamping-
45 rods interlockingly connected to said U-shaped rods for releasably securing same to end-supporting structures.

4. A device of the character described, comprising like U-shaped rods whose terminal members are reversely positioned and connected for relative longitudinal adjustments, screen-holding rods positioned across said terminal members and connected thereto interlockingly for relative longitudinal adjustments, a flexible screen positioned to cover one side of said U-shaped members and having its ends carried about the medial parts of said rods and connected removably to said screen-holding rods, and resilient clamping-rods interlockingly connected to said U-shaped rods for releasably securing same to end-supporting structures.

5. In combination, a screen-frame composed of reversed U-shaped elements assembled and connected interlockingly slidably together for relative longitudinal adjustments, and screen-carrying rods positioned interlockingly across said frame adjacent its opposite ends and having parts directed angularly along the abutting frame-elements, said rods and their said angularly-directed parts having receiving-ends for the frame-elements slideable therealong longitudinally, and said angularly-directed parts being elastically interlocked with the frame-elements.

Signed at Waterloo, Iowa, this 19th day of Nov., 1921.

HANS PETER RAVN.
